United States Patent Office

Des. 209,115
Patented Oct. 31, 1967

209,115

COOKING SURFACE OR THE LIKE

Jerry E. Wright, Corning, N.Y., assignor to Corning
Glass Works, Corning, N.Y., a corporation of New York

Filed May 27, 1966, Ser. No. 2,459

Term of patent 14 years

(Cl. D81—25)

Fig. 1

Fig. 2

Fig. 3

Fig. 4

FIG. 1 is a top plan view of a cooking surface or the like showing my new design.

FIG. 2 is a top plan view of a modified form thereof.

FIG. 3 is a top plan view of a further modified form thereof.

FIG. 4 is a top plan view of an additional modified form thereof.

The essential features of my design are shown in solid lines.

I claim:

The ornamental design for a cooking surface or the like, as shown and described.
